CLAIM

The ornamental design for a software control unit as shown and described.

DESCRIPTION

FIG. 1 is a front elevational view of a software control unit showing our new design;

FIG. 2 is a rear elevational view thereof;

FIG. 3 is a left and front perspective view thereof;

FIG. 4 is a right and front perspective view thereof;

FIG. 5 is a front, left, and bottom perspective view thereof;

FIG. 6 is a top plan view thereof; and,

FIG. 7 is a bottom plan view thereof.

In the drawings, the broken lines depict a portion of the software control unit which form no part of the claim.
